UNITED STATES PATENT OFFICE.

HENRY YOUNGQUIST, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

SHUTTLE-THREADING MECHANISM FOR AUTOMATIC FILLING-REPLENISHING LOOMS.

1,214,868.

Specification of Letters Patent.

Patented Feb. 6, 1917.

Application filed May 12, 1916. Serial No. 97,197.

To all whom it may concern:

Be it known that I, HENRY YOUNGQUIST, a citizen of the United States, residing at Manchester, county of Hillsborough, State 5 of New Hampshire, have invented an Improvement in Shuttle-Threading Mechanism for Automatic Filling-Replenishing Looms, of which the following description, in connection with the accompanying drawing, is 10 a specification, like characters on the drawing representing like parts.

This invention relates to automatic filling replenishing looms in which, as is well known, upon the complete or partial exhaustion or failure of the filling in the running shuttle means are provided for automatically ejecting the exhausted or replenished filling carrier and supplying the shuttle with a fresh filling carrier. In looms of 20 this type the shuttle is of the self-threading type, that is, a threading slot connects the recess for the filling carrier with the delivery eye, and in the operation of the loom upon the replenishment of the shuttle with a fresh filling carrier the fresh filling is carried 25 through the threading slot into the delivery eye, thus threading the shuttle. The threading slot is also provided with some retaining device which when passed by the filling in 30 its passage into the threading slot prevents the withdrawal of the filling from the threading slot and induces the subsequent passage of the filling out through the delivery eye. When the shuttle is picked from 35 the replenishing side of the loom, the end of the fresh filling is held by the hopper containing the supply of fresh filling carriers, and as the shuttle travels to the opposite side of the loom the filling passes into the threading slot and beneath the retaining means. Upon the return pick to the replenishing 40 side of the loom the thread is drawn out through the delivery eye and the shuttle is then completely threaded. If the filling is 45 not in the proper position on the pick away from the replenishing side of the loom the return pick cannot affect the threading of the shuttle, and occasionally for other reasons the filling will fail to pass out through 50 the delivery eye upon the return pick. In any such case a "mis-thread" takes place re-

sulting in breakage, a further replenishing operation, loss of picks, the necessity for arresting the take-up and letting back to prevent thin places in the cloth.

55

The object of the present invention is to provide an automatic filling replenishing loom with a means for positively insuring the threading of the shuttle upon replenishment. This object in the preferred form is 60 secured by a means acting upon transfer to seize the filling on both sides of the shuttle threading slot and positively to force the filling into threading position so that upon the return pick of the shuttle the filling necessarily passes out through the delivery eye. The invention also comprises means operating between the seizing means and the point of attachment of the fresh filling to the hopper to catch and elevate the filling, thus 65 insuring its proper alinement with the running shuttle, and placing such tension upon the filling as to insure the action of the seizing means. The invention also comprises means by which when the seizing 70 means is functioning in the shuttle it will partake of any beat-up movement of the shuttle.

75

The nature and objects of the invention in these and other particulars will more fully 80 appear from the accompanying description and drawings and will be particularly pointed out in the claims.

The drawings illustrate so much of an automatic filling replenishing loom of the 85 Northrop type as is necessary to an understanding of the present invention, together with a preferred form of mechanism embodying the present invention applied thereto.

90

In the drawings,

Figure 1 is a top plan view of the replenishing side of the loom with a preferred form of mechanism embodying this invention embodied therein, the hopper carrying 95 the supply of fresh filling carriers being shown partially in dotted lines in order not to obscure the mechanism;

Fig. 2 is a side elevation partially broken away of the parts shown in Fig. 1;

100

Fig. 3 is a front elevation of the end of the boxed shuttle with the portions of the

filling seizing means and filling catching means engaging the thread shown in position on the filling;

Fig. 4 is a transverse cross-section through the shuttle and wall of the shuttle box with the end of the filling seizing means shown in side elevation;

Fig. 5 is a view in side elevation of the filling seizing means with its rock arm shown in vertical cross section;

Fig. 6 is a rear elevation partially in vertical cross section of a detail to illustrate the means for operating the filling seizing device.

15. The general construction and operation of an automatic filling replenishing loom of the Northrop type such as is herein illustrated in connection with the present invention is well known and familiar to those skilled in the art and needs no detailed consideration. Such a loom comprises the frame 1, the breast beam 2, the lay 3 movable toward and from the breast beam, the shuttle box 4 on the lay into which the shuttle 5 is picked from the opposite side of the loom and out of which it is picked by the picker 6. The supply of fresh filling carriers 7 is maintained in a hopper shown as of the rotary type and comprising a hopper 30 stand 8 secured to the breast beam and presenting two disks one of which, 9, is provided with seats 10 for the butts of the filling carriers and the other of which, 11, supports the tips of the filling carriers. 35 This hopper also comprises an outer disk 12 over which the filling 13 from each filling carrier extends and is then secured to the holding stud 14 on the outer end of the hopper axis. In order to effect a transfer of a 40 fresh filling carrier from the hopper to the shuttle, transferring means are provided, and in this type of loom this means comprises a transerrer 15 pivotally mounted upon a stud 16 extending out horizontally from the hopper stand. The transerrer 15 is adapted at its outer end to engage the butt of the filling carrier in the hopper and is provided with a lateral extension 16 carrying a device 17 adapted to engage the tip of 45 the filling carrier. The transerrer also comprises a depending arm 18 carrying pivotally mounted thereon a dog 19 while opposite the dog and mounted upon the lay is the bunter 20. A helical spring 21 connected to the stud 16 and the transerrer 15 normally acts to maintain the transerrer elevated. Upon the call for filling replenishment the dog 19 is elevated into the path of the bunter 20 and as the lay beats up the 50 shuttle containing the filling carrier to be ejected is boxed at the replenishing side of the loom and is brought by the lay beneath the hopper; thereupon owing to the contact of the bunter 20 with the dog 19 the transerrer is swung downwardly about the stud 55

16 to engage the fresh filling carrier therebeneath in the hopper and transfer it into the shuttle thereby at the same time ejecting the depleted or exhausted filling carrier from the shuttle.

The shuttle 5 which is of the self-threading type is illustrated in Figs. 1, 3 and 4. There are many types of self-threading shuttles, but it is only necessary to illustrate one form, and it is to be understood that the invention is not to be limited to any particular form of self-threading shuttle. In these shuttles the filling carrier 7 is supported in the recess 21 open at the top and bottom of the shuttle. The delivery eye 22 extends inwardly and transversely from the outer wall of the shuttle. A threading slot 23 extends longitudinally of the shuttle from the recess 21 and vertically into the delivery eye 22, and this slot may be of various shapes and configurations according to the particular kind of shuttle eye. As the filling 13 draws off from the tip of the filling carrier in the shuttle upon the pick of the shuttle away from the replenishing side of the loom, 90 it is supposed to be carried down into the threading slot 23 and then upon the reverse pick to be passed out through the delivery eye 22 thus threading the shuttle. In order that the filling may be retained in the 95 threading slot and be guided out through the delivery eye upon the reverse pick, it is customary to provide some form of retaining means in connection with the threading slot so that when this retaining means is 100 passed by the filling in its passage into the threading slot this retaining means will prevent the withdrawal of the filling from the threading slot and insure subsequent guidance of the filling out through the delivery eye. In the form of shuttle illustrated there is shown for this purpose a metal plate 24 lining a portion of the threading slot 23 and a beak 25 projecting from one wall of the slot into a groove or recess 110 formed by a reentrant portion 26 on the plate 24 from the opposite wall of the slot. It will thus be seen that as the filling is passed down into the threading slot 23 it will ride over and beneath the beak 25 and 115 cannot then by reason of the beak projecting into the reentrant portion 26 of the opposite wall pass upwardly out from the threading slot, and hence is retained therein. The shuttle may also be provided as 120 herein shown with additional retaining means such as the finger 27 forming at its free end in connection with the tip 28 of the plate 24 a tortuous passage for the filling, but as the particular form of the retaining means is not involved in this invention it is unnecessary to describe it with further particularity.

In order to support the filling carrier in its passage from the hopper to the shuttle 130

on the lay a yielding tip support is usually provided. This is shown as comprising a rearwardly projecting arm 29 rigidly mounted on the stud 16 and having yieldingly and pivotally mounted in its end the tip support 30 which extends beneath the tip of the filling carrier in the hopper to be transferred. Upon the operation of the 10 transerrer the tip of the filling carrier rests upon this tip support 30 and the tip support yields as transfer takes place.

The mechanism thus far described is well known and familiar and is herein illustrated as disclosing one form of an automatic filling replenishing loom in connection with which the present invention is to be employed, but it is to be understood that the present invention is not to be limited to the particular construction or type of loom. 15 In automatic filling replenishing looms as already set forth when replenishment has been effected the filling will extend from the fresh filling carrier in the shuttle to its point of attachment to the hopper. The 20 shuttle is now picked to the opposite side of the loom and the filling is drawn into the threading slot 23 and should pass beneath the retaining means in the threading slot so that as the shuttle starts upon its return pick the filling will be drawn out through the delivery eye. But this designed 25 threading of the shuttle does not always take place for various reasons and with the consequent evil results already noted. The 30 present invention secures upon transfer taking place the positive forcing of the filling into threading position so that upon the return pick of the shuttle it will pass out from the delivery eye. This result as illustrated 35 is secured at the time of transfer by causing the filling to be forced beneath the retaining means in the threading slot. In the preferred form of the invention illustrated the filling is seized on both sides of the 40 threading slot and positively forced down into the threading slot beneath the retaining means, and preferably, at the same time, means are provided operating between the 45 threading slot and the point of attachment of the filling to the hopper to catch and elevate the filling, thus insuring the action 50 of the thread seizing means, insuring the proper alinement of the filling with the shuttle, and placing a required degree of 55 tension upon the filling.

In the preferred form of the invention illustrated as one means of securing the desired result the filling seizing device is pivotally mounted adjacent the transerrer and is connected thereto to be rocked thereby while the filling catching device is pivotally mounted adjacent the filling seizing device, and in turn connected thereto and rocked thereby, but in the reverse direction. As 60 shown a bearing hub 31 is located adjacent

the transerrer and for convenience is shown as formed as a part of the arm 29 of the filling carrier tip support. This hub carries a transverse shaft 32. An operating arm 33 is rigidly secured to the left hand end of the shaft 32 and at its rearward end is bent laterally to ride in a slotted projection 34 extending forwardly from the tip engaging portion 17 of the transerrer. It will thus be seen that the rocking movement of the transerrer is thus transmitted to the shaft 32. At its right hand end the shaft 32 has rigidly secured thereto a hub 35 provided with a rearwardly projecting arm 36. A rearwardly projecting rock arm 37 is pivotally mounted on the shaft 32 and yieldingly held in engagement with the projecting arm 36 by a helical spring 38 engaging at one end the rigid arm 29, and at its other end the rock arm 37. Thus the rock arm 37 rocks with the shaft 32 but is free to yield upwardly against the tension of the spring 38.

The rock arm 37 carries the filling seizing device proper which is shown as a rod 39 slidingly mounted at its forward end therein. A set screw 40 abuts a slabbed off portion of the rod 39 thus preventing twisting movement and limiting outward movement thereof while a spring 41 seated in the rock arm 37 acts normally to project the rod 39 rearwardly. At its rearward end the rod 39 is threaded and provided with a pair of lock nuts 42 between which is clamped the yoke-shaped device 43, the loop 44 therein providing for vertical and rotary adjustment with respect to the rod. The depending arms of this yoke-shaped device are each transversely forked at their lower ends to engage and seize the filling. At the proper distance forwardly from the yoke-shaped device the rod 39 is provided with a depending lug 45 so positioned as to project into the path of the shuttle-box when the seizing device is holding the filling in the shuttle, and thus cause the rod 39 with the seizing device to slide in the rock arm 37 and partake of any beat-up movement of the shuttle. 100

In the construction illustrated the disk 11 of the hopper extends somewhat over the threading slot when the shuttle is boxed ready for replenishment, and as the filling seizing device moves upwardly past the periphery of this disk it is necessary that the filling seizing device should have a lateral movement to enable it as it passes beneath the disk to move into proper position to straddle the entire threading slot and enable its two depending arms to pass down into the shuttle. By reason of this particular construction of loom illustrated it is necessary therefore to provide means for giving this lateral movement of the filling seizing device. This is secured by providing the 115 120 125 130

hub 46 of the arm 33 with a cam face 47 and the bracket 31 with a cooperating cam face 48 and inserting between the opposite end of the bearing 31 and the hub of the rock arm 37 on the shaft 32 a helical spring 49. Thus as the filling seizing device is rocked it will be given a movement around under the disk 11 and back up the side of the disk.

- 10 In the preferred form of construction illustrated the means for catching and elevating the filling between the seizing means and the point of attachment of the filling to the hopper is for convenience supported 15 by the stud 16 and operated from the rock arm 37. For this purpose the stud 16 is prolonged and provided with and carries fixedly mounted thereon the rearwardly projecting bracket arm 50. A filling catching 20 and elevating lever 51 is pivoted at 52 on the rearward end of the bracket arm 50 and is bent laterally to form an operating arm extending into a slot 54 in the rock arm 37. The rear end 55 of the lever 51 is hook shaped. The parts are so constructed and 25 positioned that when the filling seizing device moves downwardly into engagement with the filling carrying it into the shuttle, the hooked end of the filling catching device comes beneath the filling and elevates 30 it into substantial alinement with the axis of the shuttle. Thus not only is the filling properly alined but tension is placed upon the filling so as to maintain it under the 35 control of the filling seizing means and insure its being properly and accurately positioned in the threading slot of the shuttle. Upon the return of the filling seizing means upwardly to normal position the filling 40 catching device returns downwardly to its normal position.

Having fully described my invention, what I claim as new and desire to secure by Letters Patent is:

- 45 1. An automatic filling replenishing loom comprising a hopper provided with a supply of fresh filling carriers, a shuttle having an eye and a threading slot leading into the eye, means operated upon failure or exhaustion of the running filling to transfer a fresh filling carrier from the hopper into the shuttle, and means acting upon transfer to seize the filling on both sides of the shuttle threading slot and positively to force 50 the filling into threading position.

- 55 2. An automatic filling replenishing loom comprising a hopper provided with a supply of fresh filling carriers; a shuttle having an eye, a threading slot leading into the eye, and retaining means which when passed by the filling in its passage into the threading slot prevents the withdrawal of the filling from the threading slot and induces its passage out through the eye; means 60 operated upon failure or exhaustion of the running filling to transfer a fresh filling carrier from the hopper into the shuttle; means acting upon transfer to seize the filling on both sides of the said retain-

running filling to transfer a fresh filling carrier from the hopper into the shuttle; and means acting upon transfer to seize the filling on both sides of the said retaining means and positively to force the filling there- 70 past into threading position.

3. An automatic filling replenishing loom comprising a hopper provided with a supply of fresh filling carriers, a shuttle having an eye and a threading slot leading into the eye, means operated upon failure or exhaustion of the running filling to transfer a fresh filling carrier from the hopper into the shuttle; and means acting upon transfer to seize the filling, enter the shuttle at 75 both sides of the threading slot and positively force the filling down into said slot and into threading position.

4. An automatic filling replenishing loom comprising a hopper provided with a supply of fresh filling carriers; a shuttle having an eye, a threading slot leading into the eye, and retaining means which when passed by the filling in its passage into the threading slot prevents the withdrawal of the filling from the threading slot and induces its 80 passage out through the eye; means operated upon failure or exhaustion of the running filling to transfer a fresh filling carrier from the hopper into the shuttle; means 85 operated upon transfer to seize the filling on both sides of the said retaining means, enter the shuttle on both sides of the retaining means, and positively force the filling down 90 past the said retaining means into threading 95 position in the slot.

5. An automatic filling replenishing loom comprising a hopper provided with a supply of fresh filling carriers, a shuttle having an eye and a threading slot leading into the eye, means operated upon failure or exhaustion of the running filling to transfer a fresh filling carrier from the hopper into the shuttle, means acting upon transfer to seize the filling on both sides of the shuttle 100 threading slot and positively to force the filling into threading position, and means acting upon the said movement of the seizing means simultaneously to catch and elevate the filling between the seizing means 105 and its point of attachment to the hopper.

6. An automatic filling replenishing loom comprising a hopper provided with a supply of fresh filling carriers; a shuttle having an eye, a threading slot leading into the eye, and retaining means which when passed by the filling in its passage into the threading slot prevents the withdrawal of the filling from the threading slot and induces its passage out through the eye; means 110 operated upon failure or exhaustion of the running filling to transfer a fresh filling carrier from the hopper into the shuttle; means acting upon transfer to seize the filling on both sides of the said retain- 115

ing means and positively to force the filling therewith into threading position, and means acting upon the said movement of the seizing means simultaneously to catch and elevate the filling between the seizing means and its point of attachment to the hopper.

7. An automatic filling replenishing loom comprising a hopper provided with a supply of fresh filling carriers, a shuttle having an eye and a threading slot leading into the eye, means operated upon failure or exhaustion of the running filling to transfer a fresh filling carrier from the hopper into the shuttle; means acting upon transfer to seize the filling, enter the shuttle at both sides of the threading slot and positively force the filling down into said slot and into threading position, and means acting upon the said movement of the seizing means simultaneously to catch and elevate the filling between the seizing means and its point of attachment to the hopper.

8. An automatic filling replenishing loom comprising a hopper provided with a supply of fresh filling carriers; a shuttle having an eye, a threading slot leading into the eye, and retaining means which when passed by the filling in its passage into the threading slot prevents the withdrawal of the filling from the threading slot and induces its passage out through the eye; means operated upon failure or exhaustion of the running filling to transfer a fresh filling carrier from the hopper into the shuttle; means acting upon transfer to seize the filling on both sides of the said retaining means, enter the shuttle on both sides of the retaining means, and positively force the filling down past the said retaining means into threading position in the slot, and means acting upon the said movement of the seizing means simultaneously to catch and elevate the filling between the seizing means and its point of attachment to the hopper.

9. An automatic filling replenishing loom comprising a hopper provided with a supply of fresh filling carriers, a shuttle having an eye and a threading slot leading into the eye, a pivotally mounted transferrer acting when rocked downwardly to transfer a fresh filling carrier from the hopper into the shuttle, a rock arm mounted adjacent the transferrer and connected thereto to be rocked thereby, and a filling seizing device carried by said rock arm and acting when rocked downwardly to seize the filling on both sides of the shuttle threading slot and positively to force the filling into threading position.

10. An automatic filling replenishing loom comprising a hopper provided with a supply of fresh filling carriers, a shuttle having an eye and a threading slot leading into

the eye, a pivotally mounted transferrer acting when rocked downwardly to transfer a fresh filling carrier from the hopper into the shuttle, a rock arm mounted adjacent the transferrer and connected thereto to be rocked thereby, a filling seizing device carried by said rock arm and acting when rocked downwardly to seize the filling on both sides of the shuttle threading slot and positively to force the filling into threading position, and means acting upon the downward movement of the filling seizing device simultaneously to catch and elevate the filling between the seizing device and the point of attachment of the filling to the hopper. 80

11. An automatic filling replenishing loom comprising a hopper provided with a supply of fresh filling carriers, a shuttle having an eye and a threading slot leading into the eye, a pivotally mounted transferrer acting when rocked downwardly to transfer a fresh filling carrier from the hopper into the shuttle, a rock arm mounted adjacent the transferrer and connected thereto to be rocked thereby, a filling seizing device carried by said rock arm and acting when rocked downwardly to seize the filling on both sides of the shuttle threading slot and positively to force the filling into threading position, and a filling catcher pivotally mounted adjacent said filling seizing device and connected therewith and rocked in reverse direction thereby to catch and elevate the filling between the seizing device and the point of attachment of the filling to the 100 hopper. 90

12. An automatic filling replenishing loom comprising a hopper provided with a supply of fresh filling carriers, a shuttle having an eye and a threading slot leading into the eye, a pivotally mounted transferrer acting when rocked downwardly to transfer a fresh filling carrier from the hopper into the shuttle, a rock arm mounted adjacent the transferrer and connected thereto to be 110 rocked thereby, a filling seizing device mounted to slide in said rock arm and acting when rocked downwardly to seize the filling on both sides of the shuttle threading slot and positively to force the filling into threading position, means yieldingly to project said device in said rock arm, and a lug carried by said seizing device and projecting into the path of the shuttle box, whereby when the seizing device is holding 115 the filling in the shuttle it will partake of any beat-up movement of the shuttle. 120

13. An automatic filling replenishing loom comprising a hopper provided with a supply of fresh filling carriers, a shuttle having an eye and a threading slot leading into the eye, a stud extending transversely of the hopper, a transferrer mounted to rock on said stud and upon its downward movement to transfer a fresh filling carrier from the 130

hopper into the shuttle, an arm secured to and projecting from said stud, a rock arm pivotally mounted on said arm, operative means connecting the rock arm to the trans-
5 ferrer to cause the operation of the former from the latter, a filling seizing device carried by said rock arm and acting when rocked downwardly to seize the filling on both sides of the shuttle threading slot and
10 positively to force the filling into threading position.

14. An automatic filling replenishing loom comprising a hopper provided with a supply of fresh filling carriers, a shuttle having an
15 eye and a threading slot leading into the eye, a stud extending transversely of the hopper, a transerrer mounted to rock on said stud and upon its downward movement to transfer a fresh filling carrier from the

hopper into the shuttle, an arm secured to 20 and projecting from said stud, a rock arm pivotally mounted on said arm, operative means connecting the rock arm to the trans-
25 ferrer to cause the operation of the former from the latter, a filling seizing device carried by said rock arm and acting when rocked downwardly to seize the filling on both sides of the shuttle threading slot and positively to force the filling into threading position, a bracket secured to and project-
30 ing from said stud, and a filling catching lever pivoted on said bracket and operatively connected to the said rock arm to cause the operation of the lever from the rock arm.

In testimony whereof, I have signed my 35 name to this specification.

HENRY YOUNGQUIST.
